UNITED STATES PATENT OFFICE

CHARLES H. OSLUND, OF WORCESTER, MASSACHUSETTS, ASSIGNOR TO THE LIQUID CARBONIC CORPORATION, OF CHICAGO, ILLINOIS, A CORPORATION OF DELAWARE

LABEL GRIPPER FOR DUPLEX LABELING MACHINES

Application filed February 23, 1929. Serial No. 342,017.

In Patent No. 1,253,250 granted to John Emmanuel Johnson, January 15, 1918, he showed a duplex labeling machine with means for operating the grip arms and the present invention is an improvement over that.

The principal objects of this invention are to provide an improvement in the cams for operating the two grip arms which will avoid the crossing of one cam groove over the other and the corresponding difficulty of setting the cams so as to avoid interference of the moving parts, and to provide a gear construction for actuating the grip arms from the cams.

Other objects and advantages of the invention will appear hereinafter.

Reference is to be had to the accompanying drawings in which

Fig. 1 is a plan of a machine constructed in accordance with this invention;

Fig. 2 is a sectional view taken on a radial plane;

Fig. 3 is a side view of the label grip arm with a part of its operating mechanism, and

Fig. 4 is an end view of part of the same mechanism, taken from the inner end.

The invention is shown as applied to a machine comprising a rotary table 10, which is supplied with bottles from a feed turret 11 and discharges them through a discharge turret 12, a conveyor 13 being used for taking the bottles to and from the machine. This machine is rotated in any desired way through a central shaft 14 and provided with a series of stations around the circumference having means in the form of clamps 15 for holding down the articles B to be labeled.

This invention does not relate to the features just mentioned but entirely to the label grippers or grip arms 16 and 16^a and the way of operating them. Mounted in stationary position around the shaft 14 is a bearing 17 and on this are fixed two cams 18 and 19. These are split cams secured together by bolts 20 or the like and fixed independently in position on stationary bearings 17. The cam grooves are horizontal, that is, they consist of grooves 21 and 22 in the horizontal tops of the cams 18 and 19. In each of these

grooves there is a series of rollers 23 and 23^a and it will be obvious that one of these grooves is located within the other and that there is no danger of the parts operated by them coming into any conflict with each other. Consequently the two cams 18 and 19 can be set up and no care has to be taken that they register with each other in any way.

The two sets of rollers 23 and 23^a are mounted on arms 24 and 24^a fixed to vertical shafts 25 and 25^a or to gears 26 and 26^a mounted thereon. The undulations of the cam grooves therefore oscillate the gears 26 and 26^a. Each gear meshes with a gear or segment 27 or 27^a which is fixed on a radial shaft 28 or 28^a which carries on the end of it the gripper arm 16 or 16^a. On each gripper arm there is a holder 30 or 30^a for the neck label and a holder 31 or 31^a for the body label preferably.

In practice the curvature of each cam is such that these gripper arms will move from horizontal to vertical position as indicated in Fig. 3 and will operate in certain order. That is, every alternate one is connected with the next one in accordance with the curvature of a single cam. The rest of them are operated by the other cam in a corresponding order but there is not necessarily any relationship between the two series. The two grip arms next to each other can operate simultaneously or either one can operate ahead of the other.

In this way it will be seen that the possibility of any conflict in operation between the mechanism controlled by the two different cams is obviated. By having the cams horizontal, instead of vertical, plenty of room is provided for the arms and the like which are operated by them.

Although I have illustrated and described only one form of the invention I am aware of the fact that modifications can be made therein by any person skilled in the art without departing from the scope of the invention as expressed in the claims.

Therefore, I do not wish to be limited in this respect but what I do claim is:—

1. In a labeling machine, the combination with a rotary table and a series of means on

the table for clamping the articles to be labeled, of two series of label grippers arranged on the table in alternate relationship, a central vertical shaft on which the table is mounted, a pair of cams located in horizontal position around the shaft, one entirely inside the other, said cams having horizontal top faces each provided with an open top cam groove and means connected with said cam grooves for operating the label grippers.

2. In a labeling machine, the combination with a shaft and a table carried on the shaft, two series of label grippers, radial shafts on which said label grippers are mounted, two cams in the same plane surrounding the shaft, one inside the other, each having a cam groove, cam rolls in said grooves, a series of arms on which said rolls are carried, a gear connected with each of said arms to be oscillated thereby on its own axis, a gear meshing with each of said gears and each fixed on the end of one of said radial shafts, whereby said shafts will be oscillated by the cam rollers, the alternate ones being operated by the same cam, whereby each cam may be set up separately without regard to the other.

3. In a labeling machine, the combination with a vertical shaft and a horizontal table carried on the shaft, of a series of clamps on the table for the articles to be labeled, two series of label grippers carried at the circumference of the table, two horizontal cams surrounding the shaft, one inside the other, each having an open-topped cam groove, cam rolls in said grooves, a series of arms on which said rolls are carried, a gear connected with each of said arms to be oscillated thereby on its own axis, a gear segment meshing with each of said gears and two series of radial shafts to which said segments are fixed, whereby said shafts will be oscillated by the cam rollers, said shafts being equally spaced apart around the table.

45 In testimony whereof I have hereunto affixed my signature.

CHARLES H. OSLUND.
